UNITED STATES PATENT OFFICE.

S. OSCAR PARKER, OF LITTLETON, NEW HAMPSHIRE.

GLOVE.

SPECIFICATION forming part of Letters Patent No. 293,068, dated February 5, 1884.

Application filed January 31, 1883. (No model.)

To all whom it may concern:

Be it known that I, S. OSCAR PARKER, of Littleton, in the county of Grafton and State of New Hampshire, have invented certain new and useful Improvements in Gloves, of which the following is a full, clear, and exact description.

My invention relates to improvements in gloves; and it consists in the peculiar construction and arrangement of parts, as hereinafter fully described, and pointed out in the claims.

Reference is to be had to the accompanying drawings, forming part of this specification, in which similar letters of reference indicate corresponding parts in all the figures.

Figure 1 is a view of the palm side of a glove of my improved construction. Fig. 2 is a modification of the same. Fig. 3 is a longitudinal view of one of the staples. Fig. 4 is a perspective view of a glove provided with a lengthened hole for the thumb. Fig. 5 is a face view of part of the blank of a glove, showing the same provided with a lengthened thumb-hole. Fig. 6 is a blank for making a thumb.

25 A button-piece, A, is sewed to the lower end of the palm of a glove, B, and extends under the flap C, which is formed of part of the leather from which the glove is cut, so that the said flap overlaps the button-piece when the glove is buttoned or closed, whereby the glove will be closed perfectly, and no cold air can enter, and the appearance of the glove will be materially improved. The edge of the flap C can be rounded or can be made straight, as 30 may be desired. Another advantage of providing the button-piece A and the flap C covering it is that there will be a double thickness of leather over the pulse, which is the most sensitive part of the wrist, thereby protecting the same from cold more effectually than gloves of the usual construction. The button-piece A is provided at its upper end with a tongue, D, which can extend up to the thumb-hole; or it may be turned down over

45 the upper end of the slit in the glove—that is to say, over the upper edge of the flap C—thereby strengthening the upper end of the slit and preventing the same from being ripped, and acting as a gusset or stay. The button-piece can be sewed either to the inside or the outside of the glove. A button or any other

suitable fastening is attached to the button-piece A, as shown, and the flap C is provided with a button-hole or eyelet, or any other analogous device for receiving the button or 55 other fastening.

The button-piece A is an essential part of my improved glove, for if I should not sew the button-piece to the glove I would have but a single thickness of leather or other material of which the glove is made at the lower end of the palm of the glove, and in order to obtain the desired double thickness the button-piece must be attached. As mentioned above, the button-piece at the same time 60 strengthens the glove and gives it a better appearance, as it prevents the palm of the hand from showing through the slit. Wire staples E are driven through the several parts of the glove, to assist the sewing in holding the parts 65 of the glove together. For instance, one end of a staple is driven through the tongue D, at the upper end of the button-piece A, and one end through the upper end of flap C, as shown in Fig. 1. Another is driven through the 70 tongue D, through the upper part of the flap, and through that part of the glove to which the flap is sewed. A staple can also be used for holding the thumb or other parts to the glove, and can also serve as a stay to prevent 75 the ripping of the ends of the slit, as shown in Figs. 1 and 2, and to assist the tongue D in preventing the ripping of the glove at the upper end of the slit. My above-described improvements can be attached to any gloves or 80 mittens made of any material generally used in making gloves.

The gloves may be cut in such a manner that the edge of the flap will be straight or curved.

If desired, the flap C can be used without the button-piece.

The thumb-hole F in the glove is cut of such a length that it extends down to the wrist-band G, and the thumb-piece H is so cut that 95 it fits closely in the thumb-hole F, the lower end of the thumb being crossed by the wrist-band G, as shown in Fig. 4. The glove is strengthened considerably by making the thumb of such length that there is no danger 100 of tearing off the thumb by pulling on the glove, for the lower part of the thumb can be

seized very conveniently in drawing the glove on. The glove pulls off and on very easily, as there is no seam to rub against the knuckle of the thumb, and it fits better than an ordinary glove.

Having thus described my invention, what I claim as new, and desire to secure by Letters Patent, is—

1. The combination, with a glove having a flap C integral with its body, of a button-piece, A, attached to one edge of the slit and projecting under the flap, substantially as herein shown and described.

2. The combination, with a glove having a flap integral with its body, of the button-piece A, secured to one edge of the slit, and provided with the tongue D, substantially as herein shown and described.

3. A glove having its thumb-piece H made separate and extending to the lower part of the glove, and covered by the wristband G, substantially as herein shown and described, whereby the glove is strengthened and risk of tearing off the thumb avoided in pulling on the glove, as set forth.

4. The combination, with a glove having the button-piece A, provided with the tongues D, of the staples E, substantially as herein shown and described.

S. OSCAR PARKER.
